(57) **CLAIM**

The ornamental design for a portion of a tape measure, as shown and described.

DESCRIPTION

FIG. 1 is a perspective view of a portion of a tape measure showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The gray shading indicates color contrast.

The broken lines are environmental and form no part of the claimed design.
